UNITED STATES PATENT OFFICE.

CHARLES B. FOSTER, OF INDIANAPOLIS, INDIANA.

HEATING COIL.

Application filed September 26, 1924. Serial No. 740,147.

This invention relates to heating coils or radiators.

Among the objects of this invention is the provision of a heating coil, adapted to the usual methods of manufacture, as a cast iron coil, used in multiple, at the same time embodying certain advantageous features for overcoming defects in the well known types of coils now on the market.

10 In an attempt to increase the radiating area of some heating coils, a multiplicity of hollow projections, from the body of the coil units, is resorted to, forming openings in the general inside cored surface of coils, which openings are curtained over by a dropping film of condensation water, which in a measure, cuts off communication between the main cavity of the coil and the cavities of the projections.

15 One of the objects of my invention is to provide such a construction of heating coil as well as give the maximum of radiating wall area in direct contact with the body of heating medium circulating within the coils.

20 Another object of such a construction is to afford no opportunity of cutting off direct communication between parts of the radiating surfaces and the heating medium, affording better means for eliminating surface films of condensation.

25 A further object is to provide in a heating coil, a maximum of draining surface area to the radiating walls, at the same time affording ample means for drainage by the construction of the coils.

30 In a construction of heating coils, affording extra radiating area, by a multiplicity of projections, the air coming into contact with the coils becomes pocketed between the

35 projections, where they lie closely together and tends to prevent the free circulation of air, therefore, another object of my invention is to provide a construction of heating coil, the formation of the radiating surfaces

40 of which, when the coils are assembled, afford certain passages which cause the air to traverse a zig zag path, so that while permitting of a circulation of air through the assembled coils as a bank of the same, cause a mixing of the stratified layers of air, bringing all the air into contact with the radiating surfaces of the coils, increasing the radiating efficiency of the radiator.

45 A further object is to provide a heating coil construction fulfilling most of the above objects and leaving no water of condensation

within to freeze when an unused radiator is exposed to cold weather.

50 With these and other objects, my invention resides in certain construction, different embodiments of which are illustrated in the drawings, is hereinafter described, the action of which is explained and what I claim is set forth.

55 In the drawings.

Figure 1 is a side elevation of a bank of heating coils embodying my invention.

Figure 2 is an end elevation of the bank of coils shown in Figure 1.

Figure 3 is a cross section of a coil unit.

Figure 4 is a longitudinal section taken on the line 4—4 of Figure 3.

Figure 5 is an elevation of a heater, including a bank of heating coils and a housing for causing air to pass three times through the said bank.

Figure 6 is a cross section taken on the line 6—6 of Figure 5.

Figure 7 is a cross section of one of the heating coils used in the bank of coils in the heater shown in Figures 5 and 6.

80 In the figures, the coil unit 1 is shown (see Figure 3) to have three hollow leaves 2, 3 and 4 projecting in one direction and two hollow longitudinal leaves 5 and 6 projecting in the opposite direction. The exterior wall 7 of leaves 5 and 2, and the exterior wall 8 of the leaves 6 and 4 are reversely curved, while the walls 9, of the leaves 5 and 6, and the walls 10 and 11, of the leaves 2, 3 and 4 are circularly curved. The main cavity 12, of the unit 1, opens into the five longitudinal pockets 13, 14, 15, 16 and 17, of the five respective leaves 2, 3, 4, 5 and 6. At each end of a coil unit are 90 sockets 18 and 19 right and left threaded for the reception of nipples 20 which connect the units into a radiator bank 21, as shown in Figures 1 and 2.

95 The radiator bank 21 has a feed pipe 22 and a drain pipe 23, besides a housing 24, provided with deflectors 25, the purpose of which is hereinafter explained.

100 In Figures 5 and 6 is shown a bank of eighteen coils 26, having a housing 27, in which are compartments 28, 29, 30 and 31 for the circulation of air. At the entrance to the compartment 28 is a form of shutter 32. The radiator bank of coils 26 has a feed pipe 33 and a drain pipe 34.

110 A typical section of each of the coils used in the bank 26, is shown in Figure 7, in

which are six units 1, within a housing 35. Three channels 36 and six curved pieces 37 form deflectors, the use of which, is herein after explained.

5 In use, the coils as shown, are positioned to have the units horizontal, in order that best results in heating the air and in handling the condensed water, may be obtained, although the coils will operate to heat in any 10 position.

With the unit cavity 12 supplied by steam or vapor, all portions of the radiating walls as 7, 8, 9, 10 and 11 readily drain into the troughs of the leaves 2, 3 and 4 and thence 15 to the drainage end into the drain pipe 23, as shown in Figures 1 and 2, or drain pipe 34, as shown in Figures 5 and 6. There being no hollow projections on any of the walls of the units, it is readily seen that no 20 part of the radiating walls of the unit is curtained off by a dropping film of water and every part of these walls is exposed to the heating medium directly connected with the main cavity containing the same.

25 Considering the air circulation through the bank 21 of coil units 1 shown in Figures 1 and 2, where the bank is only one unit thick, air in traveling from left to right strikes the reversely curved walls 7, passes 30 upward against the curved wall 10 and is deflected downward around the leaf 5 of the unit below. Striking the wall 9 of the under unit, it is deflected around the leaf 3 of the upper unit, striking the wall 11 of the 35 upper unit where it is deflected around the leaf 6 of the lower unit and passes out between the leaves 4 of the upper and lower adjoining units, forming the passage under consideration. The curved pieces 25 above 40 and the channel 25^a below connected with the housing, assist in guiding the air in a zig zag path past the upper and lowermost units adjoining the housing.

The passage of air through the units 45 shown in the coil in Figure 7 is the same as that just described for two adjoining units of the bank 21 of Figures 1 and 2, except that it is repeated twice after passing through the first set of units, as it passes 50 through the two succeeding units, the air taking the zig zag path indicated by the arrows as it is deflected from wall to wall of adjoining units, above and below the passageway of air.

55 It is evident that so many changes in the direction of the path of the air passing through the coil, must cause a mixing of the air passing, breaking up any tendency to stratification into layers of varying temperature thoroughly saturating the air with heat giving the most freedom for radiation from the walls of the heating units on account of the movement of ever changing air.

In the case of the bank 26 of heater coils 65 shown in Figures 5 and 6, air passes into the compartment 28, of the housing 27 through the open shutter 32, thence it passes through the lower six coils of the bank 26 of heater 70 coils into compartment 29, where it rises and turns backward through the middle six coils of the said bank 26 into compartment 30; rising again and passing forward, the air passes through the upper six coils of the 75 bank 26 and out into the open compartment 31 from which it passes into the room being heated. By this means just described, the air is re-heated twice on its way through the heater. Such an arrangement of heating 80 coils in a vertical bank, in conjunction with leading compartments, may be multiplied as desired for any number of reheatings of air.

Various other modifications of my invention may be made without departing from the spirit and scope thereof, therefore I do not wish to be limited to the embodiments 85 of my invention herein shown and described.

I claim:

1. In a heating coil, a horizontally disposed heating unit, said unit having a uniform cross section thruout its length, the inner contour of any section being similar in shape and symmetrically positioned to the outer contour of said section, to have a radiating wall of uniform thickness thruout the extent of the unit, a plurality of longitudinal projections on the outer upper part of said unit forming a trough between adjoining projections, and another plurality 95 of longitudinal projections on the outer lower part of the said unit, there being a cylindrical arch between adjoining projections on the lower part of said unit.

2. In a heating coil, a plurality of heating units each similar in construction to the unit described in claim 1 and positioned relative to one another to be one above the other, to have the longitudinal projections of the upper unit occupy spaces between the longitudinal projections on the upper part of the next lower unit, whereby air passing thru the space between the units passes in a broken line course.

3. A heating device having a vertical bank 115 of like heating coils, each of said coils comprising a plurality of heating units, each of said units having a long hollow body, hollow leaves integral with said body, each running the length thereof, said leaves being so arranged on said body that in the coil, the leaves of adjoining bodies form deflectors to the passage of air through said coil, and a housing enveloping said bank of coils for guiding the air repeatedly through sections 120 of said bank of coils.

CHARLES B. FOSTER.
